JOHN D. TAYLOR, OF EDGEWOOD PARK, PENNSYLVANIA, ASSIGNOR TO THE UNION
SWITCH AND SIGNAL COMPANY, OF SWISSVALE, PENNSYLVANIA, A CORPORATION
OF PENNSYLVANIA.

SIGNALING SYSTEM FOR RAILWAYS.

1,084,765.

Specification of Letters Patent. Patented Jan. 20, 1914.

Application filed June 17, 1908, Serial No. 438,966. Renewed December 4, 1913. Serial No. 804,761.

To all whom it may concern:

Be it known that I, JOHN D. TAYLOR, a citizen of the United States, residing at Edgewood Park, in the county of Allegheny and State of Pennsylvania, have invented 5 certain new and useful Improvements in Signaling Systems for Railways, of which the following is a specification.

My invention relates to automatic block 10 signaling systems for railways which employ track circuits to control the signaling devices as to at least one of their operations.

My invention is particularly applicable to 15 electric railways in which the track rails are included in the return path for the car propulsion current to the generator.

Heretofore in many of the automatic block signaling systems insulation has been employed in one or both of the track rails 20 to separate the signaling current in one track circuit from the adjacent track circuits, and usually the distance of track between the two next adjacent insulating points has been termed a "block section." 25 Thus it will be seen that usually a block section may be said to be determined by the length of track comprised in the track circuit. In the present invention insulation is not employed in the track rails to separate 30 the signaling currents of the several track circuits, but the sources of signaling current are so arranged with regard to one another that midway between two adjacent sources there will be points of equal potential be- 35 tween the two rails. The distance of track, therefore, between two such pairs of points may be said to constitute a "block section," and in this invention a signaling device will be located at about each of such pairs of 40 points. This arrangement of points of equal potential of signaling current in the track rails may be obtained by connecting the sources of signaling current to the track at intervals in such manner that alternate 45 sources are connected in the same sense to the track, while the others are connected in an opposite sense; that is, one source will have its positive terminal connected to a given rail, while the next source on either 50 side will have its negative terminal connected to the same rail. Connected in this way, current will flow from any source through the rails to each of the sources on either side and back to the first-named

source. The rails will thus alternate in electric potential; that is, any rail that is positive at one source will be negative at the next source either side, and vice versa. Midway between the sources, therefore, the potentials of the two rails will be the same. There 55 will be a fall of potential from the positive connection of one source to the middle point between two sources in one rail, and from the opposite middle point of the other rail to the negative of the source. Therefore, a 60 relay connected to the rails between the equipotential point and a source will have an electromotive force impressed upon it due to the fall of potential between the points 65 of connection of the relay and the equipotential points. 70

When the automatic signaling system is used on a railway having an electric propulsion current for the motor cars, it is necessary to use an alternating signaling current 75 in the track circuits so as to distinguish between the signaling current and the car propulsion current. If the car propulsion current is alternating, then the signaling current must be alternating of a higher frequency. It is well understood in the art 80 that a relay can be so constructed as to respond to alternating current of a given frequency, and not to an alternating current of a lower frequency, or to a direct current. 85

In the accompanying drawings, Figure 1 is a diagrammatical view of a portion of an electric railway and the necessary parts and appliances for two block sections of an automatic signaling system embodying my invention. 90 In this figure the parts of the signaling system are illustrated in the positions they assume with no car or train present. Fig. 2 is a view similar to Fig. 1, but illustrating a modification of my invention. 95 Figs. 3 and 4 are views similar to Fig. 1, but showing a change in position of certain parts of the signaling system due to the presence of a car or train at two different points on the railway. Fig. 5 is a view similar to Fig. 100 1, but illustrating a further modification, and Figs. 6 and 7 are detail views showing one manner of increasing the impedance of portions of the track rails.

Similar letters of reference designate corresponding parts in all of the figures.

In the accompanying drawings, the sources of track circuit current are shown

as alternating current transformers which may be employed in all cases, whether electric propulsion is used, or not. It would be possible to use direct current sources for the track circuits if the motive power of the road were steam locomotives; but as this does not in any way affect the invention, the symbols representing the sources of current are all those usually employed for indicating alternating current transformers.

Referring now to the drawings for a more detailed description, Fig. 1 represents such a system as applied to a road having electric power for propelling the trains, and the generator G is the source of power for the trains. One terminal of this generator is connected to the rails through the inductive bond n , while the other terminal is connected to the usual trolley or third rail. The connection to the bond is made at the middle point of the coil, so that the propulsion current flows in opposite directions in the two halves of the coil, and thus has no magnetizing effect on the core of the bond. The generator G' is the source of alternating current for the track circuits. This is distributed to the various points where it is to be used, through the conductors j and k . The transformers T, T', etc., have their primary coils p , p' , etc., connected to these mains j and k in multiple. The secondaries s , s' , etc., are connected to the rails r , r' , in such manner that the positive terminal of s is connected to the same rail as the negative terminal of s' and the positive terminal of the secondary s^2 (not shown). Connected in this way, current will flow from the positive terminal of s' through the rail r to the negative terminal of s , thence from the positive terminal of s back through the rail r' to the negative terminal of s' . Current will also flow from s' in the opposite direction to another secondary s^2 (not shown), and back to the secondary s' . So that in each secondary coil the current will divide and go in both directions through the track, one-half flowing to the right and the other one-half to the left. This distribution of current in the rails produces points of equal potential in the rails r , r' , midway between two transformers. A relay, as R' for instance, has its armature a' connected to the rails r , r' , at some distance from the equipotential points, thus having an electromotive force impressed upon it of the same sign as that of the nearer transformer and of an amount due to the product of the impedance of the rails between the points where it is connected and the equipotential points, and the amount of current flowing in the rails.

A track relay requires a certain minimum electromotive force to be applied to its coils to cause its armature to move to close the contacts. This is known as the pick-up electromotive force. In practice, it is usual

to apply an electromotive force about twenty-five per cent. greater than this to secure reliable operation. This greater electromotive force may be defined as the operative electromotive force. If a resistance is placed in shunt around the relay coil and is gradually diminished, the electromotive force at the terminals of the coil will also gradually diminish. When it reaches a value just a little below that required to hold the contacts closed, it is known as the shunt electromotive force. In a direct current relay, the shunt electromotive force is considerably less than the pick-up electromotive force because when the contacts are closed, the armature is closer to the magnet than when the contacts are open. Consequently, a smaller current will hold the contacts closed than will close them when they are open. In most alternating current relays, however, the shunt and pick-up electromotive forces are equal, and for the purpose of this specification in which alternating current relays are assumed to be used, I will consider these two electromotive forces equal. If the electromotive force required at the terminals of the relay is known and if the current flowing in the rails from the transformer T and the impedance of the rails are known, then the distance at which the relay must be connected from the equipotential points becomes determinate. The distance required to cause the operative electromotive force to be impressed on the relay may be known as the operative distance, and it is in this sense that I have used this term in the appended claims. This distance is represented in Fig. 1 by the space between the points where the relay armature leads are connected to the rails and the points marked o o' . The shunting distance may be defined as the distance between the connections of the relay to the rail and the points where a pair of wheels rests on the rails when the shunt voltage is applied to the relay. This distance is represented in Fig. 1 by the letters r r' and is about four-fifths of the distance between the relay connections and the points o o' , assuming that the operative electromotive force is twenty-five per cent. greater than the shunt electromotive force.

The figures on the drawing near the rail, having a plus or minus sign prefixed, are intended to indicate potential. The electromotive force of a transformer secondary is assumed to be 10 volts. The connection of the positive terminal to the rail is marked plus 5, and that of the negative terminal minus 5. There will be a fall of potential from the point plus 5 where the positive terminal of the secondary s' is connected, of 4 volts, to the point plus 1 where one terminal of the armature a' is connected. A further fall of 1 volt occurs between point plus 130

1 and the point marked o . From this to the connection of the negative terminal of the secondary s , there is a still further fall of 5 volts, making the potential minus 5. The 5 positive terminal of the secondary s has a potential plus 5; and from this to the point marked o' there will be a fall of 5 volts to zero potential. From this to the other terminal of the relay armature a' there will be 10 a fall of 1 volt, making the potential of this terminal minus 1. From thence to the negative terminal of the secondary s' a fall of 4 volts makes the potential minus 5. This distribution of potential impresses an electromotive force of 2 volts on the relay armature a' . These figures are hypothetical and are merely used as illustration. The potential may have any values within reasonable limits.

20 The relay has two elements, one of which may be termed the armature and the other the field, which when energized coact to produce rotation of the armature. The field f of the relay is energized directly from the 25 signaling mains j , k . The current in the armature must bear a certain relation as to frequency and direction, to this current in the field, in order to produce the rotation of the armature. If the current in the armature 30 is reversed in direction with reference to the current in the field, then the armature will move in the opposite direction. Such a relay may be said to be polarized, and it is necessary with this system to use such a relay. If the frequency of the current in the armature differs from that in the field, no motion will be imparted to the armature. This feature, therefore, makes the relay safe 35 against being energized by the propulsion current, because it is either direct current or alternating current of a different frequency from that employed in the signaling mains. If no current at all flows in the armature, then there will be no tendency to rotate, and 40 the armature will assume a middle position due to the action of a weight, or other means, so that neither pair of contacts will be closed. The circuit for any signal, as S , will be taken through a pair of contacts e' , 45 on the relay R' , which are normally open, and another pair of contacts, d , on the relay R which are normally closed. A source of current, B , supplies current for actuating the signal when the signal circuit is closed. 50 This may be either a primary battery, or the signal operating current might be taken directly from the signaling mains, j , k , if desired.

55 Normally, all the signaling circuits will be open and the signals will stand in the danger position, as shown in Fig. 1. If a train should approach, moving in the direction of the arrow, and should reach the point to which the armature of the relay R^2 is connected, it will evidently cut off all cur-

rent from this armature and it will assume its middle position, due to the weight, so as to not close either the contacts e^2 or d^2 . It is also evident that the equipotential point will be at the points of the rails 70 bridged by the wheels and axles of the train, because current from the transformer secondary in the rear of the train cannot flow past the train, and current from the secondary s' will flow to the train. When the 75 train reaches the points o^2 , o^3 , it is evident that no effect will be produced on any of the apparatus ahead of the train, because these points are normally equipotential points, and bridging them by means of a conductor 80 of no resistance would have no effect on the distribution of current. As the train approaches the transformer T' , the equipotential point follows it, and the potential of the secondary s' falls on account of the decreased impedance in this circuit. As the potential of the secondary s' falls, the equipotential points, o , o' , will move toward it, and as the train approaches the transformer 85 the equipotential points will approach the connection of the relay armature a' . When the equipotential points o , o' reach the points where this armature is connected, the armature will be deenergized and the contacts d' disconnected. As the train approaches still 90 closer to the transformer T' , the equipotential points o , o' will pass the relay connections and lie between these connections and the transformer T' . In this position of the equipotential points o , o' , the current 95 through the relay armature a' will be the reverse of that shown in the diagram, so that the contacts e' will be closed, thus closing the circuit of signal S , which will then assume the clear position. When the train 100 arrives at the transformer T' , the equipotential points o , o' will meet it there. The relay armature a' will still be negatively energized (if we agree to term the normal energization positive), and the signal S will 105 still remain clear. As the train moves on and approaches the relay R' , the equipotential point moves with it, and when it arrives at a point somewhat nearer to the relay than the distance normally between the 110 relay and the equipotential points, but on the opposite side of the relay, the armature a' will be deenergized and go to the middle position, thus opening the circuit of the signal S , permitting it to go to the danger 115 position but still without closing the circuit of the signal S' on the contacts d' . When the rear of the train passes the relay and reaches the points o , o' , the relay will again 120 be normally energized and close the contacts d' preparatory to the next operation of the signal S' .

125 In tracing out the effects of the moving train on the relays, it is seen that the circuit of signal S has been opened a considerable 130

time before the opening in the circuit of the signal S' at d' has been closed. This time is that which elapses between the arrival of the front end of the train at the points r, r' 5 at the right of the relay R' , and the arrival of the rear end of the train at the points o, o' . There will always, therefore, be one or two signals showing danger behind the train.

- 10 The current in the relay armature is reversed by shifting the equipotential point from one side of the relay to the other. Normally, without a train on any part of the track, the equipotential points are all on 15 the same side of the relay, shown in the drawing as being at the left of the relay. The relay armatures, therefore, all stand in the same position, thus holding one pair of contacts in each signal circuit closed, and 20 the other pair of contacts in each signal circuit open. The signals, therefore, all stand normally in the danger position. When a train approaches a track circuit to which a relay is connected, it causes the equipotential 25 point to be shifted to the opposite side of the relay connections and the current to be reversed in the relay armature. This reverses the position of the armature and opens the signal contacts, which are normally closed, and closes the other pair which are normally open. The closing of the normally open contacts clears the signal ahead of the train. The equipotential point is shifted back to the other side of the relay 30 35 into its normal position by the action of the train on the same track circuit as it recedes from it.

Since the electromotive force which energizes the relay armature is dependent upon 40 the impedance of the rails between the armature and the equipotential points, or between the armature and the approaching train, where the traffic is dense and short blocks are necessary, it is desirable to have the impedance as great as possible between these 45 points, so as to permit the train to approach very close to the relay before shunting it. This is shown in Fig. 2; and in Figs. 6 and 7 I show one form of means for increasing 50 the impedance of the rail. This consists of a mass of iron surrounding as much as possible of the rail and is preferably laminated to prevent eddy currents and to prevent the signaling current leaving the rail and flowing through these masses of iron. Fig. 6 55 shows a side elevation of the rail, with the masses of iron added between the ties. Fig. 7 is a sectional view of the rail showing the iron surrounding all of the rail except the 60 part touched by the tread of the wheel. By these means I am enabled to increase the impedance of the rail about five times its normal amount, and with a given current in the rail the train can approach to within one-fifth of the distance before shunting the 65

relay that it could without these masses of iron, which, for convenience, may be termed impeders. Any variations in the shunting point of the relay which might be due to variations in conditions of the track will therefore be reduced to one-fifth their normal amount by the addition of these impeders. 70

Where the blocks may be long, the normal impedance of the rails alone may be depended upon, as in such cases the required distance of the relays from the equipotential points will be only a small percentage of the total length of the blocks. 75

Fig. 2 is similar to Fig. 1, but shows the addition of the impeders g, g' to the rails on the side of the relay toward the approaching train. 80

Fig. 3 is the same as Fig. 1, but shows a pair of wheels and an axle between the transformer T' and the relay R' , which shows that the current flowing in the relay armature a' is the reverse of that shown in Fig. 1. Fig. 4 is the same, but showing a pair of wheels and an axle at the point 90 where the terminals of the armature a' are connected. This armature is shown in its middle position, opening both the contacts e' and d' . The train in this position, however, does not affect the distribution of current ahead of it. 95

It is desirable, and in fact necessary, to connect the two rails together at intervals for the purpose of leading in or out the propulsion current from a feeder or from another track. Fig. 5 shows a means for doing this. Inductive bonds $n, n', n'',$ etc., are connected across the rails at the same points where the relays are connected and the propulsion current is led into these inductive bonds through the conductors $l, l',$ etc., which are connected to the middle points of the bonds for the purpose of balancing the current in the bond. These bonds offer sufficient reactance to the alternating track 100 circuit current to permit the relay to receive sufficient current to make it operative. They also do not interfere with the movement of the equipotential point from one side of the relay to the other. 110

The method above described of connecting the sources of current to the track affords a ready means for reversing the current through a relay automatically by the movements of a train and without the use of circuit breakers of any kind. 115

I claim:—

1. In a continuous rail signaling system, rails which are conductively continuous for all currents, sources of supply for signaling currents connected to the rails to produce shiftable points of equal potential in the two rails between the sources of supply, and a polarized signal controlling relay connected to the track rails at the operative distance 125 130

- from the normal position of each pair of equipotential points substantially as described.
2. In a continuous rail signaling system, 5 rails which are conductively continuous for all currents, sources of supply for signaling currents connected to the rails to produce points of equal potential in the two rails between the sources of supply, and a polarized relay having one of its elements connected across the track rails at the operative distance from each pair of equipotential points and whereby the current flowing through such element is reversed by the movement of 10 trains; substantially as described.
3. In an electric signaling system, track rails which are electrically continuous for both signaling and propulsion currents, and which are of substantially uniform impedance throughout, sources of supply for signaling currents, adjacent sources being oppositely connected to the track rails to provide shiftable points of equal potential in said rails between such sources, and polarized signal-controlling relays each having a winding connected across the track rails at the operative distance from the normal position of a pair of the points of equal potential; substantially as described.
4. In an electric signaling system, electrically continuous track rails, sources of supply for signaling currents connected to said rails, adjacent sources of supply being oppositely connected to the rails to produce 20 points of equal potential intermediate such sources, polarized relays having windings connected across the rails at the operative distance from each pair of equipotential points, and two signal controlling circuits controlled by each relay; substantially as described.
5. In an electric signaling system, electrically continuous track rails, sources of current supply connected to said rails, adjacent sources of supply having their unlike poles connected to the same rails to thereby produce shiftable points of equal potential intermediate the adjacent sources, and a polarized relay having an element connected across said rails between two such sources of supply, and at one side of the normal points of the equipotential; substantially as described.
6. In an electric signaling system, electrically continuous track rails, sources of supply for signaling current connected to the rails to produce points of equal potential between adjacent sources, relays having each a winding connected to the track rails at the operative distance from the corresponding pair of equipotential points, signals for two different blocks, and controlling circuits for said signals both controlled by one relay; substantially as described.
7. In an electric signaling system, electrically continuous track rails, sources of supply for signaling current connected to the rails to produce shiftable points of equal potential between adjacent sources, polarized relays having each a winding connected to the track rails at the operative distance from the normal position of each of the pairs of points of equal potential, and controlling circuits for said signals, each circuit extending between two relays and arranged to be opened by either relay; substantially as described.
8. In an electric signaling system, signals for two adjacent blocks, controlling circuits for said signals, and a polarized relay having one position in which it closes one of such circuits, and a second position in which it closes the other circuit; substantially as described.
9. In an electric signaling system, signals for two adjacent blocks, controlling circuits for said signals, and a polarized relay having one position in which it closes one of such circuits, and a second position in which it closes the other circuit and also a de-energized intermediate position in which it opens both circuits; substantially as described.
10. In an electric signaling system, electrically continuous track rails, transformers for supplying signaling current to the track rails, adjacent transformers being oppositely connected to the rails to produce points of equal potential intermediate adjacent transformers, signal controlling relays each having a winding connected across the rails near one end of a block and at the operative distance from the points of equal potential, and two signal controlling circuits controlled by each relay; substantially as described.
11. In an electric signaling system, track rails which are electrically continuous for both signaling and propulsion currents, and which are of substantially uniform impedance throughout, sources of supply for signaling currents, adjacent sources being oppositely connected to the track rails to provide shiftable points of equal potential in said rails between such sources, and polarized signal-controlling relays each having a winding connected across the track rails at the operative distance from the points of equal potential; substantially as described.
12. In an electric signaling system, electrically continuous track rails, transformers for supplying signaling current to the track rails, adjacent transformers being oppositely connected to the rails to produce points of equal potential intermediate adjacent transformers, signal controlling relays each having a winding connected to the track rails at the operative distance from the normal position of the points of equal potential; substantially as described.

across the rails near one end of a block and at the operative distance from the points of equal potential, and two signal controlling circuits controlled by each relay, together with cross connections between the rails; substantially as described.

13. In an electric signaling system, electrically continuous track rails, transformers for supplying signaling current to the track rails, adjacent transformers being oppositely connected to the rails to produce points of equal potential intermediate adjacent transformers, signal controlling relays each having a winding connected across the rails near one end of one block and at the operative distance from the points of equal potential, and two signal controlling circuits controlled by each relay, together with cross connections between the rails and to which the connections for the propulsion current are connected; substantially as described.

14. In an electric signaling system, electrically continuous track rails, transformers for supplying signaling current to the track rails, adjacent transformers being oppositely connected to the rails to produce points of equal potential intermediate adjacent transformers, signal controlling relays each having a winding connected across the rails near one end of one block and at the operative distance from the points of equal potential, and two signal controlling circuits controlled by each relay, and an inductive bond connecting the track rails adjacent to the relays and to which the connections for the propulsion current are made; substantially as described.

15. In an electric signaling system, a polarized relay having a winding connected to the track rails across one end portion of a block, a track circuit including said rails, two sources of current oppositely connected to the rails to produce points of equipotential therein which are shifted by the passage of trains to opposite sides of the connections of said winding, and two signal circuits controlled by such relay, substantially as described.

16. In a continuous rail signaling system, rails which are conductively continuous for all currents, sources of supply for signaling currents connected to the rails to produce points of equal potential in the two rails between the sources of supply and a polarized signal controlling relay connected to the track rails at the operative distance from each pair of points of equal potential and at that side only of such points in the direction from which trains approach the relays; substantially as described.

17. In an electric signaling system, sources of supply for signaling current connected to the track rails to produce points of equal potential in the rails intermediate adjacent sources, and relays connected to the track rails at the operative distance from the points of equal potential and on the side of approaching traffic only; substantially as described.

In testimony whereof, I have hereunto set my hand.

JOHN D. TAYLOR.
